UNITED STATES PATENT OFFICE

152,874

DESIGN FOR A TRAY OR SIMILAR ARTICLE

Sol Forman, New York, N. Y.

Application August 31, 1946, Serial No. 132,998

Term of patent 14 years

(CL. D44—10)

To all whom it may concern:

Be it known that I, Sol Forman, a citizen of the United States, residing at New York city, in the county of Kings and State of New York, have invented a new, original, and ornamental Design for a Tray or Similar Article, of which the following is a specification, reference being had to the accompanying drawing, forming part thereof.

In the drawing:

Fig. 1 is a top plan view of a tray showing my new design;

Fig. 2 is a side view thereof; and

Fig. 3 is a partial cross-sectional view taken on line 3—3 of Fig. 2.

The characteristic features of my design for a tray reside specifically, in the two parallel opposite plain side walls, in combination with the fluted corner areas and the oppositely disposed peaked end portions, forming the interior side walls of the tray.

I claim:

The ornamental design for a tray or similar article, as shown and described.

SOL FORMAN.
